TEMPERATURE-RESPONSIVE SWITCH MOUNTING AND INSTALLATION

Leo L. Verkuil, Norwalk, Conn., assignor to Edwards Company, Inc., Norwalk, Conn., a corporation of New York

Application October 3, 1955, Serial No. 538,140

8 Claims. (Cl. 200—138)

This invention relates to the housing, mounting and installation of temperature-responsive electric switches particularly such as are to form part of fire alarm or detector circuits or systems for the interiors of buildings, houses, and the like.

In such systems, thermostatic switches, in suitable number, are installed at suitably distributed locations and are suitably interconnected electrically to a suitable alarm or signal-transmitting device which is caused to be actuated when any one or more of the thermostatic switches responds to rise in temperature, in the building area or space in which it is located, sufficient to actuate the switch; such switches are usually located at or near the ceiling and usually are constructed or set to have different temperature-responsive ratings, such as 140° F., 180° F., or 200° F., for in some interior locations a switch of higher temperature response is appropriately employed while other spaces require switches of lower temperature response. Also, the circuits of such systems are operable, according to circumstances, at different supply voltages, usually derived from the building or house lighting circuit and, where the latter is an alternating current circuit, a step-down transformer is usually employed to obtain the desired voltage for which the particular system is constructed or rated.

One of the objects of this invention is to provide a thermostatic switch and housing that will be of compact and reliable construction and assembly and well adapted for ease and facility of installation, as in fire detecting systems of the abovementioned character. Another object is to provide a simple and practical thermostatic switch and housing or mounting therefor having coacting features of construction to facilitate manufacture and assembly and that will facilitate, in uncomplicated manner, installation according to various needs or requirements met with.

Another object is to provide a thermostatic switch mounting and installation capable of wide and dependable flexibility of rearrangement or assembly, in the field, to meet various types or standards of wiring, such as low-voltage exposed wiring, surface wiring such as armored, sheathed, or conduit-contained wiring, concealed wiring of the just-mentioned types, and the like. Another object is to provide a thermostatic switch mounting and installation capable of such flexibility of rearrangement or assembly, in the field, so that, according to need, the thermostatic switch and mounting may be directly surface-installed as on a ceiling or a wall, or assembled interiorly of a wall box particularly where flush-mounting is desired or required, or assembled exteriorly of a wall box or outlet box, all in a manner to meet the safety requirements or standards particularly with respect to various magnitudes of voltage of the circuit of the detector system. Another object is to provide a construction of the just-mentioned character in which dependable provision is made for maintaining visible, for whatever rearrangement or assembly of the parts is effected, suitable indicia

2

identifying the technical rating or other data as is or may be required, in systems of the above-mentioned character, by such authorities as the Board of Fire Underwriters.

Another object is to provide a thermostatic switch and housing of nonmetallic material and a mounting therefor of metallic material coactingly adapted for flexibility of assembly in various interrelationships according to need while maintaining suitable safety factors of insulation and the like for the resultant assemblage and the wiring leading therethrough to the thermostatic switch.

Another object is to provide a thermostatic switch sub-assembly adapted for direct installation with its thermostatic element presented for thermal response and an outlet box element to form therewith an assemblage with the sub-assembly selectively either within the box or outside of the box and in either case with the thermostatic element properly presented for thermal response from the outside of the box. Another object is to carry out the just-mentioned object in which the several parts are adapted for selective coaction, according to the method of assembly, to provide safety of wiring to the switch.

Another object is in general to provide improved constructions and installations of thermostatic switches, particularly to meet the diverse requirements of various kinds and types of wiring, in fire detector systems of the above-mentioned type, for both existing building structures and structures in course of construction. Other objects will be in part obvious or in part pointed out hereafter.

The invention accordingly consists in the features of construction, combinations of elements, and arrangements of parts as will be exemplified in the structure to be hereinafter described and the scope of the application of which will be indicated in the following claims.

In the accompanying drawings in which a preferred embodiment of the invention is shown by way of illustration and in which similar reference characters refer to similar parts throughout the several views,

Figure 1 is an elevation, as seen looking upward, of a thermostatic switch and housing sub-assembly as it appears when installed, as on a ceiling or over-head beam or the like;

Figure 2 is an end elevation as seen along the line 2—2 of Figure 1;

Figure 3 is a vertical sectional view, on an enlarged scale, as seen along the line 3—3 of Figure 1;

Figure 4 is an elevation, as seen looking upward, of an installation in which the sub-assembly of thermostatic switch and housing and a plate element of a wall box are arranged and coact for substantially concealed mounting with the thermally-responsive element of the thermostatic switch positioned substantially flush with the plane of the ceiling;

Figure 5 is a transverse sectional view, on an enlarged scale and with certain parts broken away to conserve space, as seen along the line 5—5 of Figure 4;

Figure 6 is an elevation, as seen looking upward, of an installation in which the thermostatic switch and housing sub-assembly and the plate element of the outlet box are rearranged and for wiring and mounting with the sub-assembly external of the wall box;

Figure 7 is a transverse section, on an enlarged scale and with certain parts broken away to conserve space, as seen along the line 7—7 of Figure 6, illustrating also that the wall box may be surface-mounted;

Figure 8 is an elevation as seen along the line 8—8 of Figure 2, showing in rear elevation certain parts of the sub-assembly and, partially broken away, an insulating rear terminal cover plate; and

Figure 9 is an elevation of the rear terminal cover plate alone.

While, so far as other features of my invention are concerned, the thermostatic switch may take other forms than that described, it preferably is constructed in the form of a compact unit adapted for easy assembly to other parts and provided with a thermally-responsive element that is bimetallic and preferably in the form of a concavo-convex bimetallic snap-acting disk so as to present a suitable area thereof for thermal response to the atmosphere of the building space or room in which it is to be installed in a fire detection or alarm system. In the drawings, I have designated this preferred form of thermostatic switch unit, as a whole, by the reference character TS, and its construction in general is better shown in Figures 3 and 8.

Turning first to Figure 3, the thermostatic switch unit TS comprises a cup-like casing 10 of insulating material, such as any of the moldable plastics, of round cross-section provided at its open end with an external flange 11 and having seated across its open end the snap-acting bimetallic disk 12 which is secured in position by a metallic ferrule spun over the flange 11 and the peripheral portion of the disk 12. As shown in Figure 3, the bimetallic disk 12 may be constructed, or assembled to the casing 10, so that in its normal bowed condition or shape, its convexity is toward the bottom end of the casing 10 and, upon rise in temperature, it reverses its bowed shape, doing so with a snap action as above mentioned.

Such bimetallic disks are well-known as are also various contact-making and contact-breaking arrangements to respond to this snap action for making or breaking the electrical circuit in which the thermostatic switch is connected; accordingly, any such suitable arrangement may be embodied within the cup-like casing 10 for co-action with the bimetallic disk 12 and need not be shown or described in detail. In Figure 3 I have therefore simply indicated such an internal circuit maker or breaker by the broken-line rectangle 14, its parts being electrically connected, in known manner, to two terminal and mounting lugs 15—15 of flat sheet-metal stock set into and suitably secured at the external face of the bottom of the molded casing 10 (see also Figure 8) so that they project on a diameter and in opposite directions from the casing 10, being provided, in their projecting portions each with a suitable hole for coaction with mounting and connecting screws as later described.

The parts thus far described comprise the illustrative form which the thermostatic switch unit TS preferably takes; it may be embodied in dimensionally small and compact form. For example, the bimetallic disk 12 may have a diameter on the order of $5/8$ ". The thermostatic element illustratively in the form of bimetallic disk 12, may be constructed or set, in coaction with the internal switching mechanism 14, to have any suitable temperature-responsive rating, such as 140° F., 180° F., or 200° F., and in the fire detection system in which these thermostatic switch units are to be installed, the system can oftentimes include units of different temperature responses according to the different character of the respective rooms or spaces or areas, of the building, in which they are located. It is desirable, therefore, that the respective ratings, and other technical information, pertinent to each installed unit be always visible, even though the type or form of electrical wiring or of installation of the unit vary widely, within authorized standards, and thus also dependably comply with requirements for visible identifying and rating data.

In old as well as in new building construction, various types or standards of wiring are permissible, a factor of consideration including the voltage at which the fire detection circuit or system is to operate. For example, in a low-voltage system, on the order of 25 volts, the thermostatic switch unit, such as the unit TS, may be surface-mounted, as by mounting it on the ceiling or other overhead structure, and the circuit conductors, appropriately insulated for such lower voltages, may be run along and

secured to similar surfaces. On the other hand, where the detector circuit is to operate at higher voltages, or for other reasons, the thermostatic switch unit is to be associated with a wall box, outlet box, or the like, with associated standards of wiring, and the box may be surface-mounted or flush-mounted, and in either case the thermostatic switch unit may, for various reasons, be mounted externally of the box or internally thereof. These varying conditions illustrate some of the variables met with in building structures, old or new or under construction, in installing fire alarm or detector systems, and one of the dominant aims of this invention is to provide practical and simple means for safety and dependably meeting such varying requirements.

In Figures 4 and 5 and Figures 6 and 7 I have shown two of several possible forms of installation requiring the use of a box, such as an outlet box, wall box, or the like, with which, for mounting and wiring purposes, the thermally-responsive switch, for fire detection, is to be associated, thus also to facilitate the use of such kinds or standards of house wiring or building wiring as may be desired or needed. The latter are available in various forms of construction, such as non-metallic sheathed cable or conductor, metallic sheathed conductor, conduit-carried wires, and others, and for that reason such types of wiring are not shown in the drawings. The box shown in Figures 5 and 7 is generally indicated by the reference character B and may make any suitable or desired form of which also many are known; for purposes of illustration, the box B may comprise a standard type of outlet box having a usually flat bottom 17 and integral side wall 18 which may be circular or polygonal in cross-section, being provided with threaded inwardly projecting diametrically opposed lugs 20—20 (Figures 5 and 7) and screws 21—21. As is usual, the bottom 17 or the side wall 18 or both is provided with knock-outs 22 through which, when removed, the circuit wiring is brought into the box, in the manner known in the art.

To meet varying requirements such as those indicated above, I provide a number of parts that are assembled or may be assembled in various coacting relationships, and these include a housing generally indicated by the reference character H (Figures 2, 3, 5, 6, 7 and 8) to which the thermostatic switch unit TS is initially assembled to form a sub-assembly and a mounting plate generally indicated by the reference character MP (Figures 4, 5, 6 and 7) with which the housing and switch sub-assembly is coactingly and selectively assembled and which can also serve as a cover or closure plate for the box B (Figures 4—7), being peripherally shaped, illustratively circular, to suit the shape or open end of the box, being provided with suitable means such as the diametrically opposed slot 24 and keyhole 25 (Figures 4 and 6) for coaction with the screws 21—21 to secure it in position as a closing wall of the box B. The mounting plate MP is of suitably heavy metal, conveniently in the form of a stamping, and at a suitable location therein, preferably at its center, it is provided with a relatively large opening O, which may conveniently be punched therein in stamping out the plate itself and which is round or circular and of a diameter materially greater than the outside diameter of the thermostatic disk assembly (see Figure 3), that being the outside diameter of the ferrule 13. Along the line of the diameter of central opening O and as is better shown in Figures 4, 5 and 7, I provide, equally spaced from the opening O, threaded screw-receiving holes 26—26.

The housing H (Figures 1, 2, 3, 5, 6 and 8) is in the form of a molding of cured plastic and hence insulating material and I provide it with a front wall 27 that is externally flat and which, at its center, has a round opening 28 (Figures 3 and 5) of a diameter slightly greater than the diameter of the ferrule 13 of the bimetallic disk assembly and, surrounding opening 28, is molded a collar C that projects from the front wall 27 by an amount about equal to the thickness of the mounting plate MP

and that has substantial thickness or radial dimension to provide a large annular front face upon which, as by printing or molding, is carried and displayed suitable identifying or rating data as is diagrammatically indicated at 31 in Figures 1, 4 and 6. The outside diameter of collar C is such that the collar is relatively freely receivable into the opening O (see Figures 4 and 5) of the mounting plate MP with the flat front wall 27 of housing H resting flatwise and well seated against a face of the mounting plate MP.

As better shown in Figures 3 and 8, there are molded integrally with the front wall 27 two relatively short projections or pillars 34—34 closely adjacent the round wall opening 28 and aligned along the line of the diameter of the latter; the short posts 34—34 provide inner flat faces against which the opposed sheet-metal lugs 15—15 of the thermostatic switch unit TS are brought to rest upon assembling the latter to the housing H by moving it toward the right in Figure 3, to enter the switch casing 10 into the housing opening 28, bringing the unit TS to rest with the plane of the bimetallic disk 12 parallel of the front housing wall 27 but spaced forwardly therefrom and from the front annular face of the collar C, somewhat as shown in Figure 3. The short posts 34—34 have molded into them the head ends of the two securing and connecting screws 36—36 over the threaded ends of which the apertured connector lugs 15—15 take during the above described assembly movement, whereupon the lugs 15—15 are clamped against the posts 34—34 by clamping nuts 37—37, thus securing the thermostatic switch unit TS in assembled relation to the housing H. The free threaded ends of the screws 36—36 then receive suitable washers 38—38 and nuts 40—40 respectively, whereby circuit conductors may be mechanically secured and thereby the switch mechanism 14 connected electrically into the system circuit.

The housing H has a side wall 42 (Figures 3 and 5) which can be of any suitable configuration preferably cylindrical (see Figure 8), with its axis coincident with the axis of the front wall opening 28 (Figures 3 and 5) and it extends rearwardly (to the left, in Figure 3) to terminate in an annular edge face 43 the plane of which is flat so that the housing may rest well-seated against a face of the mounting plate MP as in Figure 7 or against some other flat supporting surface such as that of a wall or ceiling or beam, indicated at 44, as shown in Figures 1 and 2.

The side wall 42 of housing H extends beyond the plane of the ends of the terminal screws 36—36 by a substantial amount (see Figure 3), in order to provide ample space to removably receive a rear terminal cover plate TP of insulating material that is peripherally seated against a ledge provided by the side wall 42 in the form of a rabbet 45 molded into the annular edge face 43 (Figures 3 and 8). With the side wall 42 of annular cross-section, the rabbet 45 and the shoulders or ledge that it forms are also circular and accordingly the terminal plate TP is in the form of a disk of suitable insulating material, conveniently stamped out of flat stock, and in the course of so stamping it for peripheral reception in the rabbet 45, I also stamp out a central round hole 46 (Figures 3, 8 and 9) that is of materially smaller diameter than the opening O in the mounting plate MP as is better shown in Figure 7, and I also stamp or punch two smaller holes 47—47 (Figure 9) that are aligned on a diameter and equidistantly spaced from the center of the terminal plate TP.

Molded integrally with the front wall 27 of housing H (Figures 5, 7 and 8) and projecting rearwardly therefrom are two pillars 48—48 aligned on a diameter of the housing H, a diameter that is at a right-angle to the diameter on which the short posts 34—34 and their respective mounting and connecting screws 36—36 are aligned; the pillars 48—48 terminate in end faces that fall in the plane of the casing rear edge face 43 (see Figures 5 and 7), they are preferably of round cross-section, and at their

rear ends they are stepped to terminate in smaller-diameter end portions which extend respectively into the smaller holes 47—47 of the terminal cover plate TP and whereby also the pillars provide annular ledges or seats 5 50—50 against which plate TP rests, coincidentally with its peripheral seating against the ledge of the rabbet 45 in the side wall 42, as is better shown in Figure 7.

In each of the pillars 48—48, there is molded a coaxial hole 51 of a diameter to freely receive a screw there-through, the hole 51 terminating, at the front face of the front wall 27, in a larger diameter, like a counterbore, as at 52 so as to accommodate therein the head of a securing screw. The spacing, along the line of the diameter, of the axes of the long screw-receiving holes 51—51 15 is the same as the spacing, along the line of the diameter of the opening O in the mounting plate MP (see Figures 4, 5 and 7), of the threaded holes 26—26 in the mounting plate MP. To selectively and coaxially assemble the mounting plate MP and the sub-assembly of housing H 20 and thermostatic switch unit TS, I provide two machine screws 53—53 (see Figures 5 and 7).

Referring now to Figure 7, let it be assumed that, to meet one type of wiring or installation requirement, a box B is required and that the sub-assembly of housing H 25 and thermostatic switch unit TS have to be or can be accommodated externally of the box B. In such case, the appropriate insulated conductors, of which two are fragmentarily shown in Figure 7 at W-1, are first brought through the large central opening O in the mounting plate MP, either before or after securing the mounting plate MP in box-closing position by screws 21, the back terminal cover plate TP, detached from the housing H, is then snaked onto the conductors to pass them through the hole 46 which is smaller than the mounting plate 30 opening O and their stripped ends or portions are then connected respectively, by the washers 38 and nuts 40, to the screw connecting posts 36—36; housing H and insulating back plate TP are then brought together to seat the insulating plate in the peripheral wall rabbet 45 and 35 against the annular shoulders or ledges 50—50 of the internal pillars 48—48 respectively, and the resultant assemblage is then brought against the front face of the mounting plate MP, substantially in the relationship shown in Figure 7; the machine screws 53—53 are then inserted 40 through the long holes 51—51 in the pillars, from the front wall 27 of the housing H, and their threaded ends 45 engaged respectively with the threaded holes 26—26 of the mounting plate MP, thereby coaxially aligning the several coaxial parts of the sub-assembly with the center 50 or axis of the large opening O in the mounting plate MP, the heads of the screws being accommodated in the recesses 52—52 so that they do not protrude from the outside face of the front wall 27 of housing H.

The clamping pressure exerted by the screws 53 is 55 taken up by the relatively heavy and strong pillars 48 (see Figure 7), protecting the molded non-metallic housing H against distortion and the housing H is held well-seated against the front face of the metal mounting plate MP and the plane of the thermostatic disk element 12 is dependably positioned to face in the desired direction such as downwardly from a ceiling. Moreover, the rear insulating terminal cover plate TP, though not directly secured to the rear of the housing H, becomes dependably locked in place to insulatingly close over the terminal connector screws and the respective wiring connections made thereat, thus providing an insulating barrier against the metal mounting plate MP, and the smaller hole 46 in the insulating plate TP becomes coaxially fixed relative to the larger opening O of the mounting plate MP, as is better shown in Figure 7, thus to provide a protective insulating ring for the opening O in the metal plate MP so that, for example, detrimental engagement of the insulated conductors W-1 with the metal periphery of the opening O is guarded against. And the 70 rating, identifying, or other data that appears on the 75

front annular face of the collar C of the thermostatic switch unit TS becomes positioned, as appears better from Figure 6, where it is indicated diagrammatically at 31, where it is always opening visible.

In Figure 7 the box B is shown as surface-mounted, as by screws (not shown) or other suitable means, to the supporting surface of the building part designated by the reference character 44, such as a ceiling, beam, or the like; it will be apparent, in view of the disclosure herein, that the box B of Figure 7 may also be flush-mounted or recessed into the ceiling or like structure, and in either case, where it is desired or appropriate to install the housing and thermostatic switch sub-assembly H-TS externally of the box, the assemblage thereof to the mounting plate MP is like that shown in Figure 7 and may be proceeded with in the manner above described. However, in either case and particularly where the box B is flush-mounted, it may be desired or required that the sub-assembly be installed internally of the box, particularly where, from the viewpoint of appearance, less obtrusiveness is desired, and in such case the installation is effected by re-arrangement of parts as is illustratively now to be described.

Such a rearrangement and different type of installation is illustrated in Figures 4 and 5, where the box is shown recessed in the ceiling 44 or like support so that the plane of its open end is substantially in the plane of the support. In this re-arrangement of the parts, the insulating back terminal cover plate TP is removed from the back of the housing H, and the latter, with the thermostatic switch unit TS assembled thereto to form the sub-assembly as above described, is placed with its flat front wall 27 against the inside face of the mounting plate MP before the latter is secured to the box, positioning the parts so that the thick-walled collar C enters the opening O in the mounting plate MP, thus permitting the flat front face of front wall 27 to be seated flatwise against the mounting plate and thus also, because of the interfitting of collar C with the plate opening O, aligning the various parts of the sub-assembly as a unit with the axis of the plate opening O. Thereby, by simple relative rotational movement, the holes 51-51 of the internal pillars 48-48 are easily brought into respective alignment with the threaded holes 26-26 of the metal mounting plate MP, whereupon the two machine screws 53-53 are inserted into the pillar holes through the rear end faces of the pillars and the threaded ends of the screws are then threaded into the threaded holes 26-26 respectively as shown in Figure 5, with the screw heads taking against the rear annular end faces of the pillars which take up the clamping pressures exerted by the screws, thus clamping and seating the front face of the front wall 27 of the housing H snugly against the inside face of the mounting plate MP, without detrimentally straining the housing H and the thermostatic switch parts carried thereby.

The circuit conductors (not shown) which can be like the conductors W-1 of Figure 7, and which like the latter, are brought into the box according to the particular type of circuit wiring desired or required, are now connected to the terminal connector screws 36-36 which, with their clamping washers and nuts, are readily accessible through the rear open end of the housing H, because of the absence of the rear insulating terminal cover plate TP. The resultant assemblage is now as a unit attached to the box B, via the screws 21-21 and the slots 24-25 (see Figures 4 and 5) with the open-ended sub-assembly of thermostatic switch unit TS and housing H carried and positioned inside of the now covered or closed-over box B, except for the collar C and the bimetallic disk 12 and part of the securing ferrule 13 which extend within and slightly beyond the collar C, somewhat as shown in Figure 5. The plane of the front face of the mounting plate MP can be coincident with the surface of the

ceiling 44 and both surfaces can be painted or finished off so that one virtually merges into the other.

Only the bimetallic disk 12 and part of its securing ferrule 13 project somewhat beyond the outer face of the mounting plate MP and the bimetallic disk 12 is dependably positioned facing the area or space to the temperature of which it is to respond upon dangerous rise; surrounding it and the ferrule 13 is the non-metallic collar C of the housing H, being in effect interposed therebetween and the metal mounting plate MP to virtually form a barrier against the drainage of heat away from the bimetallic disk by the surrounding mounting plate metal that has much greater mass and area, thus avoiding detrimental interference with the sensitiveness of temperature response of the bimetallic disk itself. At the same time, the front annular and radially-wide face of the collar C is fixedly positioned and its identifying, rating, or other data 31 (see Figure 4) carried by it is dependably maintained visible at the front of the complete installation. It will now be readily apparent, in view of the foregoing, that the installation just described, with the sub-assembly of thermostatic switch unit TS and housing H positioned inside of the box B, may be carried out with equal effectiveness in meeting various requirements or standards of safety wiring where the box B is surface-mounted as is the box B of Figure 7.

As earlier above noted, where the fire alarm or detection system operates at relatively low voltages, it is permissible to employ suitably insulated conductors that may be run along and secured to the exposed surfaces of ceilings, beams, or the like, and in such cases it is permissible to install the thermostatic switch unit on such surfaces without the intervention of special wiring accessories, such as outlet boxes or the like, as are required for higher-voltage systems. In such cases, I make provision in the housing H for mounting it, with its thereto assembled thermostatic switch unit TS, directly to and upon such surface and for ease and facility of leading the insulated wires to the interior of the housing and at the same time protectively insulating the ceiling or other surfaces from the interior terminal connectors and connections. As is better shown in Figure 3 and also in Figure 8, I provide, by molding, two cut-outs 55-55 in the side wall 42 of housing H and at diametrically opposed points therein along the line of the diameter along which are located the terminal screws 36-36; these cut-outs are open ended into the rear edge face 43 of the peripheral side wall 42 of the housing H.

By removing the insulating back cover plate TP, the circuit wires are readily connected to the terminal screws and then they are laid into either or both of the open-ended cut-outs 55, that being facilitated by the diametrical alignment (see Figure 8) of the cut-outs and terminal connectors and by the roominess within the housing H inasmuch as the pillars 48-48 are located well to either side of such diametrical alignment of these parts and, as is better shown in Figure 3, the thermostatic switch casing 10 projects but slightly into the interior of housing H. For similar reason of roominess, it might be here noted, the electrical connections necessary in completing the other types of installations above described in connection with Figures 4-5 and Figures 6-7 are made with equal facility even though the parts are relatively small.

For direct surface-installation, having laid the insulated wires in the cut-outs 55-55, the rear insulating terminal cover TP is put in place, being peripherally seated in the rabbet 45 only when the plate TP is rotationally positioned so that its two spaced small holes 47-47 (see Figure 9 and Figure 8) are coaxial with the pillars 48-48 respectively to enter the smaller-diaetered ends of the pillars 48-48 into the respective plate holes 47-47. Now, wood screws 56 are entered through the holes 51-51 of these pillars, through the front face of front wall 27, and with the back plate TP assembled as

just described, it is not necessary to have to manipulate the back plate to seek out holes or passages therein through which the screws are to pass. In this manner, the mounting of the sub-assembly directly to the surface of the ceiling or other support, indicated at 44 in Figures 1, 2 and 3, is readily completed with the driving home of the screws 56—56, the heads of which enter the recesses 52 at the outer ends of the pillar holes 51 and thereby the housing H is securely clamped to the supporting surface, with the otherwise unsecured insulating back plate TP locked in closing position and safely insulating the terminal connectors and electrical connections thereat from the supporting surface 44. The screw clamping stresses are taken up primarily by the relatively heavy pillars 43—43 without detrimentally straining the non-metallic insulating housing H.

The bimetallic disk element 12 is thus dependably installed and positioned in relation to the room or space to the temperature of which it is to respond upon dangerous rise; the collar C, surrounding it with its broad annular front face, maintains visible the desired or required identifying, rating or other data thereon, indicated at 31 in Figure 1, in this type of direct-surface installation.

It will be seen that there has been provided in this invention, a temperature-responsive electric switch and housing, mounting and installation in which the several objects hereinabove set forth, together with many thoroughly practical advantages, are successfully achieved. It will be seen that the constructions are capable of ease of fabrication and provide wide and dependable flexibility of assembly, in the field, to reliably meet varying conditions and requirements met with particularly in the wiring and installation of fire alarm or detector systems in the various types of house or building construction met with.

As many possible embodiments may be made of the above invention and as many changes might be made in the embodiments above set forth, it is to be understood that all matter hereinabove set forth or shown in the accompanying drawings is to be interpreted as illustrative and not in a limiting sense.

I claim:

1. A thermostatic switch mounting means comprising a mounting plate having a relatively large round opening therein with threaded screw holes spaced therefrom and adapted to form a closure for an outlet box, a housing of insulating material having a front wall provided with an aperture surrounded by a collar, said collar having an outside diameter so that it is receivable in said mounting plate opening, a thermostatic switch structure supported within said housing and having a part comprising a bimetallic disk positioned to substantially close off said aperture at said collar, said switch structure having terminal connectors within said housing, said housing having a peripheral side wall and a rear closure plate of insulating material and removably associated therewith, said rear closure plate having a relatively large round opening therein that is smaller than the opening in said mounting plate and that is coaxial with said collar, said housing and rear closure plate having means forming spaced screw passages of the same spacing as the threaded holes in said mounting plate, and threaded screws to extend through said passages for threading into said threaded holes from the rear end of said housing with the front wall of the latter resting against the inside face of said mounting plate and said collar received in the mounting plate opening or from the front wall with said rear closure plate resting against the outside face of said mounting plate and with the smaller opening in said insulating rear closing plate substantially coaxial with the larger opening in said mounting plate to substantially peripherally insulate the latter opening for the passage of connecting conductors therethrough to said connecting terminals.

2. A thermostatic switch mounting means comprising a mounting plate having a relatively large round opening therein with threaded screw holes spaced therefrom and adapted to form a closure for an outlet box, a housing of insulating material having a front wall provided with an aperture surrounded by a collar, said collar having an outside diameter so that it is receivable in said mounting plate opening, a thermostatic switch structure supported within said housing and having a part comprising a bimetallic disk positioned to substantially close off said aperture at said collar, said switch structure having terminal connectors within said housing, said housing having peripheral side walls terminating in a rabbeted rear edge face and said front wall having spaced hollow pillars extending rearwardly therefrom and terminating in the plane of said rear edge face, a rear cover plate of insulating material peripherally seated removably in the rabbet of said rear edge face and having cut-outs to clear said hollow pillars, said cover plate having a round opening smaller than that of said mounting plate and coaxial with said collar, and threaded screws for threaded engagement with said spaced threaded holes in the mounting plate upon passage of the screws from the rear ends of said pillars with the front wall resting against 15 the inside face of said mounting plate and said collar entered into said mounting plate opening or for passage into said pillars from the front wall of the housing with said rear edge face and insulating rear cover plate resting against the outside face of the mounting plate with 20 said two plate openings substantially coaxial so that the mounting plate opening is peripherally insulatingly overlapped.

3. A thermostatic switch mounting means comprising a mounting plate having a relatively large round opening therein with threaded screw holes spaced therefrom and adapted to form a closure for an outlet box, a housing of insulating material having a front wall provided with an aperture surrounded by a collar, said collar having an outside diameter dimensioned so that it is receivable in said mounting plate opening, a thermostatic switch structure supported from within said housing and extending into the space encompassed by said collar and positioning to the exterior of said space a thermally-responsive element, said switch structure having terminal connectors underlying said front wall at the side of said aperture, said housing having peripheral shallow side walls terminating in a rear edge face and said front wall having spaced hollow pillars of the same spacing as said threaded holes and extending rearwardly and terminating in the plane of said rear edge face, said side walls and said pillars having ledges that lie internally of said plane, a rear cover plate of insulating material seated removably at said ledges of said side walls and having spaced holes to receive the rear-ends of said pillars up to the ledges of the latter, said cover plate having a round opening smaller than that of said mounting plate and coaxial with said collar, and threaded screws for threaded engagement with said spaced threaded holes in the mounting plate upon passage of the screws from the rear ends of said hollow pillars with the front wall resting against the inside face 40 of said mounting plate and said collar entered into said mounting plate opening or for passage into said pillars from the front wall of the housing with said rear edge face and the rear ends of said pillars resting against the outside face of the mounting plate with the insulating cover plate between said outside face and said ledges and said two plate openings substantially coaxial so that the mounting plate opening is peripherally insulatingly overlapped.

4. A thermostatic switch and housing means for selective mounting by a mounting plate that has a relatively large round opening therein with threaded screw holes spaced therefrom and adapted to form a closure for an outlet box, said means comprising a housing of insulating material having a front wall provided with a round aperture surrounded by a collar of substantial radial dimen-

sion and presenting a relatively large annular front face for identifying rating indicia, a thermostatic switch structure supported from within said housing and extending into the space encompassed by said collar and positioning to the exterior a bimetallic disc corresponding to said rating indicia, said switch structure having terminal connectors within said housing, said housing having a peripheral side wall and a rear cover plate of insulating material removably associated therewith, said rear cover plate having a relatively large round opening therein that is coaxial with said collar, said housing and rear closure plate having means forming spaced screw passages from front to rear for the passage therethrough of mounting screws and whereby threaded screws may be extended through said passages for threading into said threaded holes from the rear of said housing with the front wall of the latter resting against the inside face of said mounting plate and said collar with its rating indicia received in the mounting plate opening and the indicia maintained visible or said screws extended therethrough from the front wall with said rear cover plate adjacent the outside face of said mounting plate and with the opening in said insulating rear cover plate substantially coaxial with the opening in said mounting plate for the passage of connecting conductors therethrough to said connecting terminals.

5. A thermostatic switch and housing means for selective surface mounting or mounting by a mounting plate that has a relatively large round opening therein with threaded screw holes spaced therefrom and adapted to form a closure for an outlet box, said means comprising a housing of insulating material having a front wall provided with a round aperture surrounded by a collar of substantial radial dimension and presenting a relatively large annular front face for identifying rating indicia, a thermostatic switch structure supported from within said housing and extending into the space encompassed by said collar and positioning to the exterior a bimetallic disc corresponding to said rating indicia, said switch structure having terminal connectors within said housing, said housing having a peripheral side wall and a rear cover plate of insulating material removably associated therewith, said housing and rear closure plate having means forming spaced screw passages from front to rear for the passage therethrough of mounting screws and whereby threaded screws may be extended through said passages for threading into said threaded holes from the rear of said housing with the front wall of the latter resting against the inside face of said mounting plate and said collar with its rating indicia received in the mounting plate opening and the indicia maintained visible or screws may be extended therethrough from the front wall with said rear cover plate adjacent the surface of a support and locked between the latter and the housing upon threading the screws into said support and said collar and rating indicia thereby faced forwardly of said supporting surface.

6. A thermostatic switch and housing means for selective surface mounting or mounting by a mounting plate that has a relatively large round opening therein with threaded screw holes spaced about a circle concentric with said opening, said plate being adapted to form a closure for an outlet box, said means comprising a housing of insulating material having a front wall provided with a round aperture of materially smaller diameter than that of said plate opening and bearing identifying rating indicia within an exterior annular area about the aperture of radial dimension not greater than the difference in the radii of said opening and aperture, a thermostatic switch structure supported from within said housing and extending into said round aperture and positioning to the exterior of the housing and coaxially with said annular area a bimetallic disc corresponding to said rating indicia, said switch structure having terminal connectors within said housing, said housing having a peripheral side wall and a rear cover plate of insulating material removably asso-

ciated therewith, said housing and rear closure plate having means forming screw passages from front to rear for the passage therethrough of mounting screws, said screw passages being spaced about a circle concentric with said annular indicia-bearing area and of the same diameter as the circular of spacing of said threaded screw holes of the mounting plate, whereby threaded screws may be extended through said passages for threading into said threaded holes from the rear of said housing with the front wall of the latter resting against the inside face of said mounting plate and said annular indicia-bearing area located coaxially with the mounting plate opening to fall within the projected area of the latter and the indicia maintained visible or screws may be extended therethrough from the front wall with said rear cover plate adjacent the surface of a support and locked between the latter and the housing upon threading the screws into said support and said annular area and rating indicia thereby faced forwardly of said supporting surface.

7. A thermostatic switch and housing means comprising a housing of insulating material having a front wall provided with an aperture surrounded by an external collar of relatively substantial radial and axial extent, a thermostatic switch structure supported from within said housing and extending into the space encompassed by said collar and positioning to the exterior of said space a thermally-responsive element, said switch structure having terminal connectors underlying said front wall at the side of said aperture, said housing having peripheral shallow side walls terminating in a rear edge face and said front wall having spaced hollow pillars extending rearwardly and terminating in the plane of said rear edge face, said side walls and said pillars having ledges that lie inwardly of said plane, a rear cover plate of insulating material seated removably at said ledges of said side walls and having spaced holes to receive the rear ends of said pillars up to the ledges of the latter, said rear cover plate having a round opening that is coaxial with said collar, and threaded screws for passage through said hollow pillars to secure said housing to a support and adapted when passed into said pillars from the front of the housing with the rear ends of said pillars resting against a supporting surface to clamp the pillars against the latter with the insulating cover plate locked between said supporting surface and said ledges.

8. A thermostatic switch and housing means comprising a housing of insulating material having a front wall provided with a central round aperture with two connector screws depending interiorly from diametrically opposed short posts formed in said wall, a thermostatic switch structure extending into said aperture and positioning to the exterior of said housing a thermally-responsive element, said switch structure having diametrically opposed connector lugs underlying said front wall and respectively secured to said screws, said housing having a peripheral cylindrical side wall terminating in a rear edge face and said front wall having two hollow pillars spaced on a diameter making an angle to the diameter on which lie said spaced connector screws, said pillars extending rearwardly and terminating in the plane of said rear edge face, said side wall having ledges that lie inwardly of said plane, a disk-like rear cover plate of insulating material seated removably at said ledges of said wall and having spaced holes to receive the rear ends of said pillars whereby said cover plate cannot be seated at said ledges unless it is rotatively oriented to enter the pillar ends in its holes, and threaded screws for passage through said hollow pillars to secure said housing to a support and adapted when passed into said pillars from the front of the housing with the rear ends of said pillars resting against a supporting surface to clamp the pillars against the latter with the insulating cover plate locked between said supporting surface and said ledges.
